William W. Roberts, of Hartford, Conn.
Letters Patent No. 1621 dated Aug. 5, 1862.

The schedule, referred to in these Letters Patent and making part of the same,
To all whom it may concern:

Be it known that I, William W. Roberts of the
City and County of Hartford and State of Connecticut, have invented or
produced a new and original design or pattern for Burial Caskets, and
I do hereby declare that the following is a full and exact description of
the same, reference being had to the accompanying photographic views, in
which the same letters indicate like parts.

In the accompanying drawings or photographic
views is shown a new and original design for a burial casket.
a. a' are sides and ends of the casket ornamented with moulding c.

d, are flattened corners, - e, is the lid proper, having a glass opening g, and moulding c', configurated thereon, h, is a lid for the glass opening. The whole combined to produce a rich and ornamental design for a burial Casket.

What I claim therefore and desire to secure by Letters Patent, is the design or pattern for a burial casket substantially as here-in illustrated, and described.
